UNITED STATES PATENT OFFICE.

FREDERIC WILKES, OF WILKINSBURG, PENNSYLVANIA.

METHOD OF AND APPARATUS FOR SEPARATING OIL FROM WATER.

Application filed February 15, 1927. Serial No. 168,318.

My invention relates to a method of and apparatus for separating oil from water, and particularly to the removal of water from apparatus wherein oil is required but the presence of water in appreciable quantities is detrimental.

One object of my invention is to provide a means and a method for the removal of water from apparatus, such as water-cooled bearings, the bearings of water pumps, water-cooled oil transformers, etc.

Another object of my invention is to provide an improved means for lubricating machinery and for removing water from the lubricant.

Still another object of my invention is to simplify and improve generally the methods and apparatus for removing oil from water, or for separating other liquids of different specific gravities.

Some of the ways in which my invention may be practised are shown in the accompanying drawings, wherein Figure 1 is an elevational view, partially in section, of a portion of a shaft-bearing structure and a lubricating system therefor, and Fig. 2 is an elevational view, partially in section, of an electrical transformer to which my invention is applied.

Referring to Fig. 1, I show an oil system for automatically maintaining a supply of lubricant within a bearing chamber 3. The lubricant supply is maintained in a manner similar to that described and claimed in my Patent No. 1,579,586, issued April 6, 1926, and comprises an oil container or reservoir 4 that has screw-threaded connection with an oil cup 5, and is provided with a check valve 6, which is normally held open by a stem 7 of the oil cup 5, to permit oil to flow from the reservoir 4 through a conduit 8-8^a to the bearing 3. It will be understood that oil may be supplied to the chamber 3 from any other suitable source.

A motor shaft or other rotating member 9 extends into the bearing chamber 3 and is supported in suitable bearings, which may have water cooling passages 10. An oil ring 11 is loosely supported upon the shaft 9 and is slowly rotated during movement of the shaft 9, in a manner well known in the art, to carry oil from the oil pool 12 to the shaft.

In bearings of this type, there is not only condensation of vapor, which causes an objectionable accumulation of water in the

body of oil within the bearing chamber, but leakage may occur from the passages 10; or in the case of a shaft which is employed to drive a centrifugal water pump, leakage of water may take place along the shaft past stuffing boxes and bearings and accumulate in the bearing chamber to an objectionable degree.

In order to remove such water as may gather within the chamber 3, I provide a device which will now be described:

Between conduit sections 8 and 8^a, I introduce a well or water-collecting chamber 13, disposed at a point below the bottom of the oil chamber 3. Oil from the reservoir 4 will flow through the chamber 13 to the chamber 3, in the manner indicated by the arrows.

Any water present in such oil supply or which tends to accumulate in the chamber 3 will flow to the bottom of the well 13 in the manner indicated by the dotted arrows. An overflow pipe 14 is provided through which water may rise from the bottom of the well 14. It will be understood that as water accumulates in the well 13, it will rise in the pipe 14, displacing any small amount of oil which may have previously entered said pipe, and eventually flow over the upper edge of such pipe. The water is prevented from backing up in the conduit 8^a and in the chamber 3, by reason of the head of oil within said chamber, because the upper end of the pipe 14 is at about the desired normal level of the body of oil within the chamber 3, although such level may rise still higher above the upper end of the pipe 14, if a large amount of water has accumulated in such pipe. The oil within the chamber 3 is therefore at all times maintained substantially free of water.

In Fig. 2, I have shown an electrical transformer casing 16 within which the primary and secondary coils (not shown) of the transformer may be mounted, the body of oil being provided for preventing overheating of the coils. In order to prevent overheating of the oil, water-cooling coils (not shown) are provided, these coils being supplied through a water inlet 17 and the water after passing through the cooling coils passes out through an outlet 18.

It is, of course, essential that no water be permitted to accumulate in the transformer chamber, and in order to prevent such accumulation, I provide a water-collecting

chamber 13^a that has an overflow pipe 14^a which extends to a point near the top of the transformer, an outlet 19 being provided at a point near the upper end of the pipe. A glass gage 20 is connected, at its ends, to the pipe 14^a, so that the level of the liquid within the transformer may be observed. Water which enters the transformer chamber will flow out of the bottom thereof, through a conduit 21 to the chamber 13^a, and be forced upwardly through the overflow pipe 14^a, by reason of the head of oil in the transformer, as in the case of the structure of Fig. 1.

From the foregoing it will be seen that I provide means for maintaining a substantially water-free body of oil, and one that is sufficiently separated from the water that has been removed therefrom as to avoid danger of intermingling of the oil and water, as through agitation of the chambers containing the same, since the bodies of oil and

water have communication with one another only through a conduit of small diameter. It will also be seen that the invention is applicable to the separation of other liquids, of different specific gravities. 25

I claim as my invention:

The combination with a bearing having an oil reservoir box and a source of oil supply therefor, of a conduit leading from said source into the lower portion of the reservoir, a water-collecting chamber disposed below the conduit and having communication therewith, and an overflow pipe extending upwardly from said chamber to a point 30 above the conduit and not materially higher than the desired normal oil level in said reservoir.

In testimony whereof I the said FREDERIC WILKES have hereunto set my hand.

FREDERIC WILKES.
